(57) **CLAIM**

The ornamental design for a weight training band, as shown and described.

DESCRIPTION

FIG. 1 is a top, front and right side perspective view of a weight training band showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 1.

The dash-dot broken lines define the boundary of the enlarged view and form no part of the claimed design.

1 Claim, 9 Drawing Sheets
